UNITED STATES PATENT OFFICE

127,203

DESIGN FOR AN OVERBOOT

Leslie H. L'Hollier, Waltham, Mass., assignor to
The B. F. Goodrich Company, New York, N. Y.,
a corporation of New York

Application February 24, 1941, Serial No. 99,179

Term of patent 14 years

To all whom it may concern:

Be it known that I, Leslie H. L'Hollier, a citizen of the United States, residing at Waltham, in the county of Middlesex and Commonwealth of Massachusetts, have invented a new, original and ornamental Design for an Overboot, of which the following is a specification, reference being had to the accompanying drawing, forming a part thereof, of which:

Fig. 1 is a view in elevation of the overboot as seen from the left side showing my new design.

Fig. 2 is a view in elevation of the boot as seen from the right side.

I claim:

The ornamental design for an overboot, as shown.

LESLIE H. L'HOLLIER.
